UNITED STATES PATENT OFFICE.

EARNEST E. LYNCH, OF HILMAR, AND HOMER A. MEAD, OF TURLOCK, CALIFORNIA,
ASSIGNORS TO MASTERENCH CORPORATION, A CORPORATION OF CALIFORNIA.

WRENCH.

Application filed November 21, 1921. Serial No. 516,589.

To all whom it may concern:

Be it known that we, EARNEST E. LYNCH, a citizen of the United States, residing at Hilmar, in the county of Merced, State of California, and HOMER A. MEAD, a citizen of the United States, residing at Turlock, in the county of Stanislaus, State of California, have invented a new and useful Wrench, of which the following is a specification, in such full and clear terms as will enable those skilled in the art to construct and use the same.

This invention relates to improvements in wrenches and the object of the invention is to provide an adjustable wrench that will automatically grip various shapes and sizes of nuts.

Another object is to provide a wrench that will adjust itself to different sizes of nuts and grip the flat sides only without slipping and thereby prevent injury to the corners of the nut.

Another object is to make a wrench with a swinging jaw that will act like a ratchet on the nut and thus save time over other types of wrenches.

Another object of the invention is to so arrange one face of the movable jaw of the wrench as to give it the greatest holding effect possible, its angle with respect to the radius of movement thereof being about 90 degrees. Variations in said angle may be made but to produce a good wrench the angle should be as nearly that indicated in Fig. 3 as possible.

Another object of the invention is to so arrange the movable jaw with respect to the handle as to give the effect of an open end wrench.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a side elevation of the wrench.

Fig. 2 is a plan of the wrench, and

Fig. 3 is a detail view of the jaws to illustrate the action thereof.

The numeral 1 indicates the main body of the wrench which has the handle portion 2 with the hole 3 for convenience in hanging up the wrench. The jaw 4 has the rounded surface 5. The swinging jaw 6 has a shank

7 extending into a slot in the handle, and is pivoted on the pin 8.

A projection 9 on the shank is acted on by the spring 10 which is secured and held in tension by the pin 11.

The swinging jaw 6 has the jaw portion with the three surfaces 12, 13, 14 in the relation of a portion of a hexagon. The surfaces 12 and 5 form the gripping means between the jaws 4 and 6.

The action of the wrench in operation is as follows: The jaw 6 is hooked over the nut with the surface 12 in contact with a side as shown in Figure 1. The handle 2 is pulled in the direction of the arrow A, which will move the jaw 4 in the direction of the arrow B, and thus the surface 5 will move in the path of motion C around the center pin 8.

It will be noted that the path of motion C cuts into the hexagon nut, therefore, the continued pull on the handle tends to force the nut against the surface 12 of the jaw 6, and the harder the pull the tighter the grip. By moving the handle back the jaw 6 slips over to the next surface of the nut and the action can be repeated rapidly. The surface 12 should be at a right angle to a line D drawn from the corner E to the center 8, said radial line cutting the movable jaw where the faces 12 and 13 intersect each other.

It will be seen that the reason for providing that the distance from the jaw face 12 to the pivot shall be substantially twice the distance from the center of the pivot to the handle jaw face 5 is to allow the proper length along the jaw face 14 when a nut almost twice as large as the nut shown in Figure 1 is attempted to be turned, and to provide the movable jaw with proper grip on the nut at all times.

The path of travel of the movable jaw is such that, when it is fully opened, the wrench will hold a hexagonal nut, one side of which is as long as the face 13.

What we claim is as follows but various modifications may be made in the construction shown in the drawings and above particularly described form, within the purview of our invention.

1. A wrench comprising a bar with a fixed jaw on one end and a handle on the other, and a swinging jaw pivoted thereto adjacent the fixed jaw, said swinging jaw having

a flat gripping surface extending substantially at right angles to a radial line passing through the pivot center and said gripping surface where it intersects another flat gripping surface of the movable jaw, the said intersection being substantially double the distance from the pivot center that said pivot center is from the intersection of the aforesaid radial line with the outer face of 10 the fixed jaw when the movable jaw is closed.

2. A wrench comprising a bar having a fixed jaw with a rounded gripping surface,

on one end and a movable jaw pivoted adjacent the fixed jaw the pivot lying on one side of the handle axis and the jaw extending across said axis in all its movements, the fixed jaw also extending across said axis and inclining toward the direction in which the pivoted jaw moves from the closed position. 15 20

In testimony whereof we have hereunto set our hands this 11th day of November, A. D. 1921.

EARNEST E. LYNCH.
HOMER A. MEAD.
